ATTORNEY.

UNITED STATES PATENT OFFICE.

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

PADLOCK.

1,271,382.

Specification of Letters Patent.

Patented July 2, 1918.

Application filed December 27, 1917. Serial No. 209,056.

To all whom it may concern:

Be it known that I, ELMER B. STONE, a citizen of the United States, residing at New Britain, in the county of Hartford and

5 State of Connecticut, have invented a new and Improved Padlock, of which the following is a specification.

My invention relates to the class of devices above named, and an object of my invention, 10 among others, is to provide a device of this class having means to enable a laterally swinging shackle to be readily engaged with the keeper opening in the case.

One form of lock embodying my invention and in the construction and use of which the objects herein set out, as well as others, may be attained, is illustrated in the accompanying drawings, in which—

Figure 1 is a view in side elevation of a 20 padlock embodying my invention with parts broken away to show construction, the shackle being shown in its unlocked position.

Fig. 2 is a view in cross section through 25 the same looking from the bottom end and with the shackle swung to one side.

Fig. 3 is a view similar to Fig. 2 but with the shackle in the same position as shown in Fig. 1.

30 Fig. 4 is a view showing a little different embodiment of the invention.

In the accompanying drawings the numeral 5 indicates the case of a padlock that may be of any ordinary form and construction 35 and including a key cylinder 6 that may be operated in the usual manner by means of a key, and that is provided with a bolt operating prong 7 engaging a shoulder 8 on a locking bolt 9 mounted for sliding 40 movement in the case and having a nose 10 to engage a locking notch 11 in the short arm 12 of a shackle. The long arm 13 of the shackle extends into a well 14 in the case in which is also located a spring 15 for forcing 45 the shackle to its outward or open position. All of the parts thus far described may be of any ordinary and well known construction.

The shackle is of that type having a lateral swinging movement when it is in its outward position, a pin 16 engaging within 50 an annular groove in the long arm of the shackle to retain it in the case while permitting such rotary movement. This pin is 55 also located in a recess 17 formed in the

side of the long arm of the shackle and opening into said groove, the recess permitting longitudinal movement of this arm of the shackle.

My present invention provides means for automatically moving the shackle to a position so that the short arm 12 will be opposite the keeper opening 18 in the case, and in the form of device herein shown for effecting this purpose I provide a positioning plunger 19 having its end "squared" to engage a flat surface on the shackle, said flat surface being positioned to receive the end of the plunger 19 when the short arm 12 is opposite the keeper opening 18. Preferably this positioning surface 20 constitutes the bottom of the recess 17, and a spring 21 is employed to force the plunger against said positioning surface, and, as in the structure herein shown, this spring may, if desired, serve the double purpose of a bolt actuating spring as well as a plunger actuating spring. In order to facilitate the closing movement of the shackle the outer edge of the plunger may be beveled, if desired, to cooperate with the beveled surface at the end of the recess 17.

In the form of the device as shown in Fig. 4 the plunger also serves a function as an auxiliary lock bolt, it being provided with a nose 22 to engage a notch 23 in the long arm of the shackle and thus aid in locking the shackle in its closed position. The end of this nose 22 is "squared" to engage the positioning surface 20 as in the structure hereinbefore described and operating in the same manner to position the short arm of the shackle.

In the operation of the lock the shackle having been released by withdrawal of the bolt 9 by means of a key in the usual manner the shackle will be forced outwardly by the spring 15 to the position shown in Fig. 1. The shackle may now be manually swung to one side (see Fig. 2) until the end of the plunger 19 encounters the round surface of the long arm 13 of the shackle. When thus in contact with said round surface the latter will remain in any position in which it may be placed. When, however, the end of the plunger encounters the corner at either edge of the flat surface 20 on the shackle then the latter will be forced to its central position (see Fig. 1) with its end opposite the keeper opening 18. It will thus be seen 110

that under certain conditions the shackle is "self-centering" and that the short arm 12 of the shackle may be moved to a considerable extent in either direction from its 5 central position while these conditions exist and that, therefore, little care will be required to place the short arm of the shackle in position to cause the plunger to "center" said short arm.

10 Different arrangements of mechanism for automatically positioning the short arm of the shackle opposite the keeper opening 18 may be employed, and I do not, therefore, desire to confine my invention to the ar- 15 rangement of parts herein shown and de- scribed, and in accordance with the pro- visions of the patent statutes I have de- scribed the principles of operation of my in- vention, together with the lock which I now 20 consider to represent the best embodiment thereof; but I desire to have it understood that the lock shown is only illustrative and that the invention may be carried out by other means.

25 I claim—

1. A padlock including a case, a shackle movable longitudinally in the case and having a lateral swinging movement therein, and means to return the shackle to its nor- 30 mal position with the short arm thereof opposite a keeper opening in the case and after it has been swung to one side.

2. A padlock including a case, a shackle movable longitudinally therein and having 35 a lateral swinging movement, and means co- operating with the long arm of the shackle to return said shackle to its normal position with the short arm of the shackle opposite a keeper opening in the case after the shackle 40 has been moved to one side.

3. A padlock including a case, a shackle movable longitudinally in the case and hav-

ing a lateral swinging movement therein, and means including a positioning plunger coöperating with the long arm of the shackle 45 and engaging a flat positioning surface to move the shackle to its normal position.

4. A padlock including a case, a shackle movable longitudinally in the case and hav- 50 ing a lateral swinging movement therein, said shackle also having a flat positioning surface, and a positioning plunger mounted in the case and having a "squared" end to engage said flat positioning surface on the shackle to return it to its normal position. 55

5. A padlock including a case, a shackle movable longitudinally in the case and hav- 60 ing a lateral swinging movement therein, the long arm of the shackle having a recess to receive a retaining pin, the bottom of said recess being provided with a flat position- 65 ing surface, a positioning plunger mounted in the case and having a "squared" end, and means for forcing the plunger against said positioning surface to return the shackle to its normal position.

6. A padlock including a case, a shackle movable longitudinally in the case and hav- 70 ing a lateral swinging movement therein, a locking bolt to engage said shackle, a po- sitioning plunger mounted in the case, a spring located between the plunger and bolt and exerting force on both, the long arm of 75 said shackle having a flat positioning sur- face to be acted upon by said positioning plunger.

7. A padlock including a case, a shackle movable longitudinally in the case and hav- 80 ing a laterally swinging movement therein, and means to effect swinging movement of the shackle to place it in a predetermined position and to resist movement in different directions from said position.

ELMER B. STONE.
